YARN CARRIER CONTROL MECHANISM FOR STRAIGHT KNITTING MACHINES

Paul Schmidt, Wyomissing, Pa., assignor to Textile Machine Works, Wyomissing, Pa., a corporation of Pennsylvania

Application April 26, 1934, Serial No. 722,426

20 Claims. (Cl. 66—130)

This invention relates to yarn carrier control mechanism for straight or full fashioned knitting machines, and particularly to those equipped with shock absorbers adapted to reduce the force of impact occurring between the longitudinally reciprocable thread carrier rods of the machine and the travel stops carried by the narrowing nuts at the opposite ends respectively of the machine.

Reciprocation of the carrier rods, between the travel stops, is effected through the medium of a friction box which is rigidly connected to one or more of the carrier rods. The friction box is slidably mounted on, and frictionally grips, a longitudinally reciprocable drive rod. The drive rod receives uniform and invariable axial reciprocation, to an extent greater than the greatest possible movement of the carrier rods between the travel stops with the narrowing nuts separated to their fullest extent, by what is known as the Coulier motion of the machine. The excess movement of the drive rod, over and above the immediate requirement of the carrier rods, is taken up by relative sliding motion being effected between the friction box and the drive rod, after the carrier rods, which are operatively connected to the friction box, engage the travel stops at the end of the machine toward which the friction box is moving.

The force of the impact between the carrier rods and the travel stops is adapted to be reduced to substantially a minimum by the friction box engaging speed-reducing abutments respectively located adjacent to the opposite ends of the path of travel of the carrier rods, one of which, at the time of such engagement, is traveling in the same direction and at substantially the same speed as, or slightly less than, that of the friction box, whereby practically no impact between the friction box and the abutment is effected.

After engagement of the friction box with the speed-reducing abutment, the speed of travel of the abutment is progressively lessened, between the time of said engagement and the time of engagement of the carrier rods with the travel stops at the end of the machine toward which the rods are traveling.

As a result of such progressive lessening of the speed of the abutment, the speed of the friction box, and consequently the speed of the carrier rods attached thereto, is progressively lessened and the force of impact between the carrier rods and travel stops is thereby substantially reduced.

After the carrier rods have engaged the travel stops at the end of the machine toward which the friction box and drive rod are moving, the drive rod continues to move through the arrested friction box for the remainder of that particular stroke of its reciprocatory movement.

Sudden reversal of the friction box drive rod, in beginning the next or reverse stroke of its

reciprocatory movement, causes a relative sliding movement between the drive rod and the friction box before and until the inertia of the friction box and that of the carrier rods connected to the friction box is overcome, after which the friction box and the carrier rods move as a unit with, and at the same speed as, the drive rod.

In order to make the shock absorber fully effective, the friction box must arrive at a definite point in its travel, i. e. the point at which the friction box initially engages the abutment of the shock absorber, at the exact moment at which the shock absorber is traveling at substantially the same speed, and in the same direction, as the drive rod. Due to the fact that the extent of slippage occurring between the drive rod and the friction box, before the inertia of the friction box and carrier rods is overcome, varies at different times, it has been practically impossible at each and every stroke of reciprocation of said friction box to coordinate the movement of the shock absorber abutment with the movement of the friction box for most effectively performing its function.

One object of the present invention is to provide means whereby the movement of the friction box with and by the drive rod will be uniform and regular at the beginning of and throughout each and every stroke of reciprocation of the drive rod, whereby the friction box, as it nears the end of each stroke of reciprocation, will make contact with the abutment of the shock absorber at the proper time to receive full benefit of the slowing up effect provided by the progressively decreasing travel of the shock absorber abutment before the carrier rods connected to the friction box make contact with the travel stops.

With this and other objects in view, which will become readily apparent from the following detailed description of the illustrative embodiment of my invention shown in the accompanying drawings, my invention resides in the novel elements, features of construction, mechanisms and combination of parts in cooperative relationship, as hereinafter more particularly pointed out in the claims.

In the drawings:

Figure 1 is a longitudinally contracted plan view of sufficient of a straight, or flat, knitting machine of the type above noted to illustrate the operation of the mechanism of the present invention as applied thereto;

Fig. 2 is rear elevation of the mechanism at one end of the machine illustrated in Fig. 1;

Fig. 3 is a transverse sectional elevation taken on the line 3—3, Fig. 2;

Fig. 4 is a rear elevation of a portion of the mechanism shown in Fig. 3, showing the coordinating mechanism of the present invention in detail;

Fig. 9 is a longitudinal sectional elevation similar to Fig. 5, and taken on the line 9—9, Fig. 8;

Fig. 10 is a longitudinal sectional elevation 15 taken on the line 10—10, Fig. 3 showing certain portions of the coordinating mechanism on an enlarged scale;

Figs. 11 and 12 are views similar to Fig. 10 showing various positions of the elements of the 20 coordinating mechanism illustrated therein;

Figs. 13 and 14 are respectively a perspective and side elevation of a detail of the invention; and

Figs. 15 to 18 inclusive diagrammatically illustrate the operation of the mechanism of the present invention in coordination with the mechanism of the machine.

Figs. 1 and 2 disclose various parts of a Reading full-fashioned stocking machine embodying the 30 mechanism and elements of my invention. For the sake of clearness I have illustrated only those parts of the various mechanisms necessary for an understanding of the invention; the various other parts and mechanisms and their manner 35 of operation are well known in the art, and are shown and described in detail in the "Reading" Full Fashioned Knitting Machine Catalogue (copyright 1929) published by the Textile Machine Works, Reading, Pennsylvania.

40 As shown in Figs. 1 and 2, the machine comprises end frames 1 and 2 and center frames 3, 3 which are rigidly connected by a longitudinal front beam 4, a longitudinal back beam 5 and a longitudinal center bed 6.

45 Slidably mounted in guideways 7, 7 which are supported by brackets 8 is a series of longitudinally reciprocable thread carrier rods 10. The brackets 8, 8 in turn, are secured to the center beam 6.

50 Slidably mounted in bearings 11, supported by brackets 12 which are secured to the center frames 3, is the friction box drive rod 13. Mounted on and frictionally gripping the drive rod 13 are the friction boxes 15 and 15a shown 55 in Figs. 1 and 2 respectively.

The friction boxes 15 and 15a are provided with transversely slidable coupling bars 16 and 16a which are adapted to engage the dogs 17 on one, each or any of the carrier rods 10, whereby said 60 carrier rod or rods may be selectively and rigidly connected to the friction boxes 15 and 15a. It will be observed that the friction box 15a (see Fig. 2), a number of which are positioned in various sections of the knitting machine, and operate in well known manner, is of the usual construction and forms no part of the present invention; whereas, the friction box 15 (see Fig. 1), located near the middle of the machine and operating in manner hereinafter described more in 70 detail, is so constructed as to be adapted to cooperate with shock absorber mechanism of the type set forth in Meyer U. S. Patent No. 1,750,017.

Secured to the drive rod 13, against all relative movement with respect thereto, is a cross head 18. 75 The cross head 18 is carried by a base 19 which

in turn is secured to the Coulier slide box 20. The slide box 20 is connected by a link 21 to the outer free end of the long rocker arm 22 of the Coulier motion, the opposite end of said rocker arm being pivoted at 23 to a bracket 24 which is 5 rigidly secured to the back beam 5.

Pivotedly connected at 25 to a bracket 26, which is secured to the back beam 5, is the short rocker arm 27 of the Coulier motion, the free end of which is connected by the pitman 28 to the long 10 rocker arm 22, intermediate the ends thereof, in a manner illustrated in the "Reading" catalog previously referred to.

Rotatably mounted on the pitman 28 is the usual pair of relatively spaced rollers 29, 29 which 15 operate, in diametrically opposed relation to each other, against the peripheral edge of the Coulier cam 30. The Coulier cam 30, as usual, is driven from the main shaft of the machine (not shown), whereby for each course of stitches produced by 20 the needles of the machine, the drive rod 13 is moved longitudinally in one direction to move the selected carrier rod or rods 10 in a corresponding direction for laying a thread, or threads 25 respectively, controlled thereby to the needles of the machine for forming the said course of stitches; and whereby, for the formation of the next course of stitches, the drive rod 13 and the carrier rod or rods 10 are moved in an opposite direction to complete one cycle of reciprocation 30 of the drive rod 13, which provides two needle-traversing movements of the carrier rods 10.

At each end of the machine is provided a narrowing screw 31 on which is mounted a narrowing nut 32. On each narrowing nut is a series 35 of travel stops 33, one for each of the carrier rods 10. During shaping of the fabric, as produced, for example, by transferring stitches from some to others of the needles of the machine, the screws 31 at the opposite ends of the machine are 40 rotated to move the nuts 32 toward each other or away from each other, as the case may be, whereby the travel stops 33 are similarly moved to decrease or increase the extent of the longitudinal needle-traversing movement of the carrier rods 10 accordingly.

As above noted, the reciprocation of the drive rod 13 is uniform while the reciprocation of the carrier rods 10 varies in accordance with the relative positions of the travel stops 33 at the 50 opposite ends of the machine, and, in order to provide for such variations in the reciprocations of the carrier rods 10, the extent of reciprocation of the drive rod 13 exceeds the greatest possible extent of reciprocation of the carrier rods 10 and 55 the excess movement of the drive rod 13 is taken up by the drive rod 13 sliding through, and relative to, the friction box 15 after the friction box has been brought to rest by reason of the carrier rods connected thereto having engaged the travel 60 stops 33 at that end of the machine toward which the drive rod 13 is moving at the time.

Pivotedly mounted on a stud 34 on each of the narrowing nuts 32, is a bell-crank lever 35. To the outer end of one arm 36 of each of said bell-crank 65 levers 35 is pivotally connected, at 37, one end of a rod 38. The rods 38, 38 extend in opposite directions to each other, toward the middle of the length of the machine respectively, and substantially parallel, and adjacent to the path of 70 movement of the drive rod 13 and the friction box 15 thereon, the inner ends of said rods 38, 38 being mounted for axial sliding movement in suitable bearings (not shown) carried by the center frames or other rigid portions of the ma- 75

chine. The rods 38, 38 are in no wise connected one to the other, and are adapted for independent axial movement relative to each other.

On each of the rods 38 is rigidly secured an abutment 40 which is adapted to be engaged by a tongue 39. The tongue 39 may be either pivoted to, or slidably mounted on the friction box 15 for movement in a plane transversely to the axis of said friction box, whereby the tongue 39 may be moved into or out of line with the abutments 40, 40 on the shock absorber rods 38, 38 respectively.

Normally the tongue 39 projects laterally from one side of the friction box 15 for engagement with the abutments 40, 40 alternately, near the opposite ends respectively of the strokes of reciprocation of the friction box 15.

The second arm 41 of each bell-crank 35 is provided with an adjustable stop 42. The stop 42 in each instance is adapted to rest on a shelf plate 43 which is carried by and extends laterally from and parallel to the center bed 6. The stops 42, 42 are normally maintained in engagement with the positioning shelves 43, 43, at the opposite ends respectively of the machine, by springs 44 each having one end attached to a collar 45 which is secured to the rod 38 which is operatively connected to the particular bell-crank 35. The opposite end of the spring 44 is connected to an arm 46 secured to and projecting from the narrowing nut 32 on which the bell-crank 35 is pivotally mounted.

The arm 41 of the bell-crank 35, in each instance, is provided with a roller 47 which under predetermined conditions is adapted to enter one end 48 of a cam groove 49. The cam groove 49 is formed in a cam block 50 which is secured to an extension 51 of the slur cock bar 52 of the machine. The slur cock bar 52, as usual, is slidably mounted for longitudinal reciprocation concurrently with the friction box drive rod 13, said slur cock bar being rigidly connected to the Coulier slide box 20 by which the drive rod 13 receives its reciprocation.

As shown in Fig. 3, the cam blocks 50 are slidably mounted on and guided by guide bars 53. The guide bars 53 are supported by and from the center bed 6 through brackets 54 which are secured to the bed 6. The guide bars 53 are rigidly secured to the brackets 54 by bolts 55. The positioning shelves 43 are also supported by the brackets 54, to which said shelves are rigidly connected by bolts 56.

As shown in Fig. 2, the cam groove 49 in each cam block 50 is provided with a peak 57 which is disposed at a relatively higher elevation than the substantially common plane of the opposite ends 48 and 58 respectively of said cam groove, whereby, as the cam blocks 50 are reciprocated relative to the rollers 47, the rollers 47, riding in the cam grooves 49, rock the bell-crank levers 35 and thereby effect reciprocation of the shock absorber rods 38, 38, respectively.

Operation of the shock absorber at either or both ends of the machine will be clearly understood by referring to Figs. 1, 15, 17 and 18. As shown in Fig. 15, the drive rod 13, the friction box 15, and the carrier rod 10, connected to said friction box have previously been moved toward the left, as viewed in said figure, until the end 10b of the carrier rod 10 has engaged the travel stop 33 at the left end as viewed from the back of the machine.

During such movement the slur cock bar 52 has been similarly moved and as a result there-

of the cam block 50 at the right end of the machine has moved into the position relative to the cam roller 47, of the bell-crank 35 at the right end of the machine, as illustrated in Fig. 15.

Continued rotation of the Coulier cam 30 in the direction of the arrow in Fig. 2, by which the drive rod 13 and slur cock bar 52 previously have been moved toward the left, causes a reverse movement of the drive rod 13 and slur cock bar 52, in the direction of the arrow a (Fig. 15).

Movement of the drive rod 13 in the direction of the arrow a will carry the carrier rod 10 in a like direction, the slur cock bar 52 also moving in the direction of said arrow. Before the tongue 39 in the friction box 15 engages the abutment 40 on the shock absorber rod 38 at the right side of the machine, as viewed in Fig. 15, the cam block 50 at said right side will have moved to such an extent that the cam roller 47 thereon has arrived at the mouth 58 of the cam groove 49, as illustrated in Fig. 16, and advanced up the incline of the cam path toward the peak 57 thereof, as shown in Fig. 17, whereby the cam groove 49 has rocked the bell-crank lever 35 in a direction to move the abutment 40 toward the approaching tongue 39.

As the roller 47 arrives at the peak 57 of the cam groove 49 and the movement of the cam block 50 in the direction of the arrow a continues (see Fig. 17) the bell-crank lever 35 at said right side of the machine begins to rock in an opposite direction carrying the right abutment 40 in the direction of the arrow a. Substantially at this moment the tongue 39 on the friction box 15 makes contact with the right abutment 40, without any perceptible impact.

The drive rod 13 and slur cock bar 52 continue to move in the direction of the arrow a, but, due to the shape of the cam groove 49 between the peak 57 and the low portion 48 of said cam groove, the travel of the rod 38 and the abutment 40 is progressively lessened.

The right end 10a of the carrier rod 10, at such time, is closely approaching the travel stop 33 at the right end of the machine and due to the slowing up of the motion of the carrier rod 10 and the friction box 15, as the result of the engagement of the tongue 39 with the right abutment 40, the speed of the carrier rod 10 has been so reduced that the end 10a thereof engages the right travel stop 33 without any perceptible impact.

The cam roller 47 of the right bell-crank 35 at the same time or immediately preceding or immediately following the contact with the end 10a of the carrier rod 10 with the right travel stop 33, depending upon the position of the right narrowing nut 32 with respect to the extreme limit of reciprocation of the rod 13, rides out of the mouth 48 of the cam groove 49, as clearly illustrated in Fig. 18.

The cam block 50, by movement of the slur cock bar 52 in the direction of the arrow a through Figs. 15, 16 and 17 moves from the position shown in Fig. 2 to that shown in Fig. 18 preparatory to movement of the drive rod 13 and slur cock bar 52 to the left, in the direction of the arrow b, as illustrated in Fig. 18.

When the drive rod 13 and friction box 15 thereon move in the direction of the arrow b, Fig. 18, the carrier rod 10 will likewise be moved in the direction of the arrow b, to complete one cycle of reciprocation together with the drive rod 13 and slur cock bar 52, whereby the thread con-

trolled by the carrier rod 10 will be laid to the needles of the machine for the formation of a second course of stitches.

From the foregoing, it will be obvious that the tongue 39 on the friction box 15 must engage the abutment 40 at a critical point in the relative movement between the cam block 50 and the cam roller 47 of the shock absorber at the end of the machine toward which the friction box 15 is moving. It will also be obvious that variation in the time of pick up of the friction box 15 by the driving rod 13 will materially affect the time of engagement of the tongue 39 with the abutment 40.

The present invention particularly concerns means by which the pick up of the friction box 15 by the drive rod 13 will be constant and regular and for this purpose certain of the carrier rods 10, at points respectively spaced inwardly from the opposite ends 10a and 10b thereof, are provided with shoulders 60, 60. These shoulders are each adapted to be engaged by a shoulder 61 formed on a broad faced latch 62 which is pivotally mounted on an axis 63 transverse to the rods 10 between a pair of lugs 64, 64 formed on a housing 65. The housings 65 are secured to the narrowing nuts 32, 32 respectively by bolts 66 (see Fig. 3).

As there is a shock absorber associated with each of the narrowing nuts 32, there is likewise a controlling latch 62 and associated elements at each end of the machine.

The latch 62 in each instance is provided with an arm 67 on the outer end of which is rotatably mounted a roller 68. The roller 68 is adapted to ride on a cam surface 69 formed on a slide 70 (see Figs. 13 and 14) which is mounted in a groove 71 formed on the upper surface of the housing 65 and extends transversely of the carrier rods 10. The carrier rods 10 extend through an opening 72 formed in each of the housings 65.

The roller 68 of the latch 62 in each instance is held in contact with a cam surface 69 formed on the slide cam 70, by means of a spring 73 having one end attached to a post 74 carried by the latch 62 and its opposite end attached to a post 75 carried by the housing 65 (see Figs. 4 and 5).

One end of the slide cam 70 in each instance is pivotally connected at 76 to one end of a lever 77, the opposite end of which is pivotally connected at 78 to an extension 79 of the housing 65. The lever 77 is provided with a cam roller 80 which is adapted to be engaged by a cam 81 formed on or carried by an extension 51 of the slur cock bar 52. The cam roller 80 in each instance is maintained in engagement with the slur cock extension 51 and/or the cam 81 carried thereby by a spring 82 having one end attached to the lever 77 and its opposite end secured to a bracket or shoe 83 carried by and secured to the outer end of the bell-crank pivot stud 34 and which maintains sliding contact with the underside of the shelf 43 during movement of the narrowing nut 32 by the narrowing screw 31. The pivot stud 34 in each instance is rigidly secured in, and extends laterally from, the narrowing nut 32 on which the bell-crank lever 35 is mounted.

The cam 81 at each end of the machine bears a definite relationship longitudinally of the slur cock bar 52 and its extensions 51, 51 with respect to the cam block 50 at the opposite end of the machine, which will be readily understood upon referring to Fig. 15, wherein the latch 62 at the left side of the machine is shown as holding the carrier bar 10 during initial movement of the slur cock bar 52 and drive rod 13 during the initial

portion of the movement of the drive rod and slur cock bar in the direction of the arrow a (Fig. 15), until the roller 80 on the slide cam actuating lever 77 at the left end of the machine comes into a position at the base of the incline 81a of the cam 81 at the left side of the machine.

As the cam 81 continues to move in the direction of the arrow a (Fig. 15) the roller 80 begins to ascend the incline 81a of said cam thereby rocking the lever 77 and sliding the cam 70 across the 10 housing 65. As the slide cam 70 is moved longitudinally with respect to the roller 68 of the latch 62 the roller 68 moves down the incline portion 69a of the slide cam 70 from the position shown in Fig. 7 toward the position shown in Fig. 8, and the spring 73 controlling the latch 62 accordingly rocks the latch 62 to have a bodily component of movement in the direction of operative movement of the carrier rod 10, from the position shown in Figs. 5, 15 and 10 toward the position shown in Fig. 11, which permits the carrier rod 10, under the influence of the drag created by a portion of the drive rod 13 in passing through the friction box 15, to begin to move longitudinally by reason of the shoulder 61 on the latch swinging outwardly 25 from a plane coinciding with that of the shoulder 60 on the carrier rod 10 into a plane disposed at an angle to the plane of the shoulder 60, as clearly shown in Fig. 11.

As the roller 80 further ascends the incline 81a 30 the slide cam 70 is moved still further with respect to the cam roller 68 of the latch 62 whereby said cam roller 68 rides into the lowest depressed portion 69b of the cam surface 69 on the slide 70, which permits the latch 62 to be rocked further 35 about its pivot whereby the carrier rod 10 gains momentum under the influence of the drag of the friction box 15 on the drive rod 13.

At the moment when the roller 80 has reached the top of the incline 81a of the cam 81 and the 40 cam roller 68 has reached the lowest depressed portion 69b of the cam 70 the point 61a of the latch 62 disengages with a snap action from the point 60a of the shoulder 60 on the carrier rod 10, as shown in Fig. 12, thereby completely releasing 45 the then moving carrier rod 10 to continue its movement away from the latch, as shown in Fig. 9, with, and at the same speed as, the drive rod 13 and friction box 15 thereon.

In this manner, the uncertainty of the time 50 of pick up of the friction box by the drive rod 13 is eliminated and the inertia of the carrier rod 10 and the friction box 15 is overcome during and by the slight amount of movement permitted for the carrier rod 10 by the rocking of the latch 55 62 from the position shown in Fig. 10 through the position in Fig. 11, to the position shown in Fig. 12 in which the carrier rod is shown as just released from the latch 62. Because the inertia of the rod 10 and friction box 15 has been overcome before the latch 62 releases the carrier rod 10, the pick up of the friction box by the drive rod 13 is effected at the same moment in each and every stroke of reciprocation of the carrier rod 10.

It will, therefore, be apparent that, in view of the accurately timed release of the carrier rod by the cam 81 at one end of the machine, the cam block 50 at this end of the machine will be caused 70 to engage the tongue 39 of the friction box 15 at the exact and proper moment for the friction box to receive substantially the maximum slowing up action provided by the abutment 40 as effected through the declining portion of the cam 75

slot 49, between the peak 57 of said cam slot and the end 48 thereof.

For purposes of adjustment, the latch 62, in each instance, is made in two parts, the one part 5 on which the shoulder 61 is formed being substantially U-shape in form and provided with a pair of bosses 90, 90 through which the pivot shaft 63 of the latch 62 extends, said bosses being provided with set screws 91, 91 respectively 10 by which the pivot shaft 63 is secured against movement in the bosses 90 (see Fig. 6). Between the bosses 90, 90, the portion of the latch 62 on which the arm 67 for the roller 68 is formed is provided with a hub or boss 92, and threaded into 15 the boss 92 and engaging the pivot shaft 63 of the latch 62 is a set screw 93 by which the arm portion of the latch may be rigidly secured to the shaft 63 in definite fixed relation to the shoulder portion of the latch 62.

20 The post 74, which affords the anchorage for the one end of the spring 73, is in the form of an adjusting screw, threaded into and through a lug 94 formed on the arm portion of the latch 62 and engaging an abutment on the shoulder portion of 25 the latch, whereby to slacken the set screw 93 and turn the adjusting screw 74 will effect relative rotation between the two portions of the latch 62 about the common pivot 63 thereof, whereby the relation of the roller 68 on the latch 30 to the shoulder 61 thereof may be varied.

The shoulder 60 on the carrier rod 10 is formed by one edge of a plate 95 secured to the carrier rod in any suitable manner.

The cams 81, 81 are so arranged on the slur- 35 cock bar extensions 51, 51 that the latch 62, at the end of the machine toward which the carrier rods happen to be moving is held in a raised position to permit the plate 95 to pass thereunder, as shown at the right side of Fig. 17, 40 whereupon as soon as the shoulder 60 on the plate passes the shoulder 61 of the latch the cam 81 lowers the latch to the carrier rod holding position shown in Fig. 18, ready for the beginning of the reverse movement of the drive rod 13.

45 If for any reason it may be desirable to throw the latches 62 out of action, the slide 70 in each instance is provided with a notch 96 (see Figs. 13 and 14) into which may be dropped the free end of a detent 97, carried by the housing 65, 50 when the slide 70 is moved longitudinally to an extent greater than its normal movement by the cam 81, whereby the roller 80 will be raised clear of the cam 81 and the latch 62 will be raised to an inoperative position such as the position shown 55 in Fig. 9, in which case the carrier rods 10 and the plates 95 thereon may move freely through the housing 65.

Of course, the improvements specifically shown and described, by which I obtain the above re- 60 sults, can be changed and modified in various ways without departing from the invention herein disclosed and hereinafter claimed.

I claim:

1. In a straight knitting machine, the combi- 65 nation of a thread carrier, friction drive means for said carrier, means restraining said carrier during initial carrier-propelling movement of said drive means, means movable with and substantially at the same speed as said drive means at a 70 predetermined point in said carrier-propelling movement thereof for diminishing the speed of the carrier, and means for effecting gradual initial movement of the latter before releasing it from said restraining means at a relatively ear- 75 lier predetermined point in said carrier-propel-

ling movement of said drive means for coordinating the movements of the carrier and the speed-diminishing means at the point of synchronization of said movements of the speed-reducing means and the drive means.

2. In a straight knitting machine, the combination of a thread carrier, friction drive means for said carrier, means restraining said carrier during initial carrier-propelling movement of said drive means, means movable with and substantially at the same speed as said drive means at a predetermined point in said carrier-propelling movement thereof for diminishing the speed of the carrier, means for effecting gradual initial movement of the latter before releasing it from 15 said restraining means at a relatively earlier predetermined point in said carrier-propelling movement of said drive means for coordinating the movements of the carrier and the speed-diminishing means at the point of synchronization of 20 said movements of the speed-reducing means and the drive means, and means for gradually reducing the speed of said carrier speed-diminishing means relative to the speed of said drive means.

3. In a straight knitting machine, the com- 25 bination of a thread carrier, friction drive means for said carrier, travel stops for said carrier, means restraining said carrier during initial car- 30 rier-propelling movement of said drive means, means movable with and substantially at the same speed as said drive means at a predetermined point in said carrier-propelling movement thereof for diminishing the speed of the carrier, means for effecting gradual initial movement of the latter before releasing it from said restrain- 35 ing means at a relatively earlier predetermined point in said carrier-propelling movement of said drive means for coordinating the movements of the carrier and the speed-diminishing means at the point of synchronization of said movements 40 of the speed-reducing means and the drive means, and means for gradually reducing the speed of said carrier speed-diminishing means relative to the speed of said drive means as said carrier approaches one of said travel stops. 45

4. In a straight knitting machine, the combination of a thread carrier, friction drive means for said carrier, travel stops for said carrier, relatively movable elements supporting said stops for increasing and decreasing the travel of said car- 50 rier, means on said stop supports for restraining said carrier during initial carrier-propelling movement of said drive means, means on said stop supports and movable with and substantially at the same speed as said drive means at a prede- 55 termined point in said carrier-propelling movement thereof for diminishing the speed of the carrier, means on said stop supports and operable by means operating concurrently with said drive means for effecting gradual initial move- 60 ment of the carrier before releasing the latter from said restraining means at a relatively earlier predetermined point in said carrier-propelling movement of said drive means for coordinating the movements of the carrier and the speed- 65 diminishing means at the point of synchronization of said movements of the speed-reducing means and the drive means, and means operating concurrently with said drive means for gradually reducing the speed of said carrier speed-diminishing means relative to the speed of said drive means as said carrier approaches one of said travel stops. 70

5. In a straight knitting machine, the com- 75 bination of a carrier rod, a reciprocating drive

- rod, a friction box affording a yielding coupling between said rods, means for restraining the carrier rod and friction box during initial carrier rod propelling movement of the drive rod, an abutment in the path of movement of the carrier rod and friction box, means for moving the abutment at substantially the same speed as the drive rod at a predetermined point in the course of the carrier rod propelling movement of the drive rod, and means for effecting gradual initial movement of the carrier rod before releasing the latter from the restraining means at a relatively earlier predetermined point in said movement of the drive rod for synchronizing the movement of the friction box and carrier rod with the movement of the abutment at the first said point in said movement of the drive rod.
6. In a straight knitting machine, the combination of a carrier rod, a reciprocating drive rod, a friction box affording a yielding coupling between said rods, means for restraining the carrier rod and friction box during initial carrier rod propelling movement of the drive rod, an abutment in the path of movement of the carrier rod and friction box, means for moving the abutment at substantially the same speed as the drive rod at a predetermined point in the course of the carrier rod propelling movement of the drive rod, means for effecting gradual initial movement of the carrier rod before releasing the latter from the restraining means at a relatively earlier predetermined point in said movement of the drive rod for synchronizing the movement of the friction box and carrier rod with the movement of the abutment at the first said point in said movement of the drive rod to effect a non-impacting coupling between the abutment, the friction box and the carrier rod, and means for slowing up the speed of the abutment friction box and carrier rod relative to the drive rod subsequent to the effecting of said coupling.
7. In a straight knitting machine, the combination of a carrier rod, a reciprocating drive rod, a friction box affording a yielding coupling between said rods, a travel stop for said carrier rod, means for restraining the carrier rod and friction box during initial carrier rod propelling movement of the drive rod, an abutment in the path of movement of the carrier rod and friction box, means for moving the abutment at substantially the same speed as the drive rod at a predetermined point in the course of the carrier rod propelling movement of the drive rod, means for effecting initial movement of the carrier rod before releasing the latter from the restraining means at a relatively earlier predetermined point in said movement of the drive rod for synchronizing the movement of the friction box and carrier rod with the movement of the abutment at the first said point in said movement of the drive rod to effect a non-impacting coupling between the abutment, the friction box and the carrier rod, and means for slowing up the speed of the abutment friction box and carrier rod relative to the drive rod subsequent to the effecting of said coupling and prior to engagement of the carrier rod with said travel stop to reduce the impact between the carrier rod and the travel stop.
8. In a straight knitting machine, the combination of a carrier rod element, a reciprocating drive rod, a friction box element affording a yielding coupling between said rods, relatively spaced travel stops for the carrier rod, relatively movable supports carrying said stops respectively, means on each support for restraining the carrier rod during initial carrier rod propelling movements of the drive rod, means mounted on each support for diminishing the speed of the carrier rod as it approaches the travel stops including abutments each arranged to travel with the drive rod at predetermined points respectively in the carrier rod propelling movements of the drive rod for engagement with one of said elements as the carrier rod approaches one of said travel stops, means for diminishing the speed of the engaged abutment subsequent to said engagement, and means for effecting gradual initial movement of the carrier rod before releasing the latter from said restraining means at a relatively earlier predetermined point in said propelling movement of the drive rod.
9. In a straight knitting machine having a longitudinally reciprocable carrier rod and friction drive means therefor, decelerating means engageable by the carrier rod at a predetermined point in the travel of said rod, a latch pivoted adjacent said rod for effecting a progressively decreasing retarding action of the carrier rod during initial movement thereof by said drive means, a cam slidable transversely of the rod and the latch for actuating and finally releasing the latch from the carrier in predetermined timed relation to the engagement of the carrier with said decelerating means.
10. In a straight knitting machine having a longitudinally reciprocable carrier rod and friction drive means therefor, decelerating means engageable by the carrier rod at a predetermined point in the travel of said rod, a latch pivoted adjacent said rod for effecting a progressively decreasing retarding action of the carrier rod during initial movement thereof by said drive means, a cam slidable transversely of the rod and the latch for actuating and finally releasing the latch from the carrier in predetermined timed relation to the engagement of the carrier with said decelerating means, and means operable concurrently with said drive means for actuating said slide cam.
11. In a straight knitting machine having a longitudinally reciprocable carrier rod and friction drive means therefor, decelerating means engageable by the carrier rod at a predetermined point in the travel of said rod, a latch pivoted adjacent said rod for effecting a progressively decreasing retarding action of the carrier rod during initial movement thereof by said drive means, a cam slidable transversely of the rod and the latch for actuating and finally releasing the latch from the carrier in predetermined timed relation to the engagement of the carrier with said decelerating means, and cam means operable concurrently with said drive means for actuating said slide cam.
12. In a straight knitting machine having a longitudinally reciprocable carrier rod and friction drive means therefor, decelerating means engageable by the carrier rod at a predetermined point in the travel of said rod, a latch pivoted adjacent said rod for effecting a progressively decreasing retarding action of the carrier rod during initial movement thereof by said drive means, a cam slidable transversely of the rod and the latch for actuating and finally releasing the latch from the carrier in predetermined timed relation to the engagement of the carrier with said decelerating means, lever mechanism for actuating said slide cam, and cam means operable concurrently with said drive means for actuating said lever mechanism.

13. In a straight knitting machine having a longitudinally reciprocable carrier rod and friction drive means therefor, decelerating means engageable by the carrier rod at a predetermined point in the travel of said rod, a latch pivoted adjacent said rod for effecting a progressively decreasing retarding action of the carrier rod during initial movement thereof by said drive means, a cam slideable transversely of the rod and the latch for actuating and finally releasing the latch from the carrier in predetermined timed relation to the engagement of the carrier with said decelerating means, lever mechanism for actuating said slide cam, cam means for operating said lever mechanism, and cam means for operating said decelerating mechanism in timed relation to each other.

14. In a straight knitting machine having a longitudinally reciprocable carrier rod and friction drive means therefor including a longitudinally reciprocable drive rod and a friction box affording an operative connection between said carrier rod and said drive rod, decelerating means engageable by the carrier rod at a predetermined point in the travel of said rod, a latch pivoted adjacent said rod for effecting a progressively decreasing retarding action of the carrier rod during initial movement thereof by said drive means, a cam slideable transversely of the rod and the latch for actuating and finally releasing the latch from the carrier in predetermined timed relation to the engagement of the carrier with said decelerating means, lever mechanism for actuating said slide cam, cam means for operating said lever mechanism, cam means for operating said decelerating mechanism in timed relation to each other, and a bar longitudinally and synchronously reciprocable with said drive rod and carrying said cams in predetermined relation one to the other.

15. In a straight knitting machine having a longitudinally reciprocable frictionally driven carrier rod, a restraining element for said carrier rod, a slide cam for operating said restraining element, a lever pivoted adjacent to the carrier rod about an axis transverse to the rod and operatively connected to the slide cam, and means operable in predetermined timed relation to the reciprocation of the carrier rod for rocking said lever to effect gradual initial movement of the carrier rod before releasing it from the restraining element.

16. In a straight knitting machine having a longitudinally reciprocable frictionally driven carrier rod, a restraining element for said carrier rod, a slide cam for operating said restraining element, a lever pivoted adjacent to the carrier rod about an axis transverse to the rod and operatively connected to the slide cam, and a cam reciprocably parallel to the carrier rod in predetermined timed relation to the reciprocation thereof for rocking the lever to effect gradual initial movement of the carrier rod before releasing it from the restraining element.

17. In a straight knitting machine having a longitudinally reciprocable carrier rod, a shoulder on said rod, a latch pivoted adjacent said rod, a shoulder on the latch engaging the shoulder on the rod, a cam slideable transversely of the rod, a cam roller carried by the latch, a spring for

rocking the latch with the roller on contact with said cam, and means for sliding the cam in predetermined time relation to the reciprocation of the carrier and to effect release of the rod from the latch.

18. In a straight knitting machine having a longitudinally reciprocable carrier rod, a shoulder on said rod, a two part latch pivoted adjacent said rod, a shoulder on one part of the latch engaging the shoulder on the rod, a cam slideable transversely of the rod, a cam roller carried by the second part of the latch, a spring for rocking the latch with the roller in contact with said cam, means for sliding the cam in predetermined time relation to the reciprocation of the carrier to effect release of the rod from the latch, and means for adjusting one part of the latch about the pivot of the latch and relative to the second part of the latch to vary the angular relation of the shoulder on the one part to the roller on the second part for minutely timing the release of the carrier rod from the latch.

19. In a straight knitting machine, the combination of a carrier rod, a drive rod, a friction box affording a driving connection between said rods, a slur cock bar, means for reciprocating said drive rod and slur cock bar in synchronization, relatively spaced narrowing nuts, travel stops for the carrier rod respectively mounted on said narrowing nuts, a bracket on each narrowing nut, a latch on each bracket for restraining the carrier rod during initial movement of the drive rod and slur cock bar, an abutment carried by each narrowing nut for engagement with the friction box, cams on the slur cock bar for operating said abutments for decelerating the friction box and carrier rod prior to the latter's engagement with the travel stops, and cams on the slur cock bar in predetermined relation to each other and to the abutment operating cams thereon for effecting gradual initial movement of the carrier rod before releasing the latches from the carrier rod in predetermined relation to the engagement of the friction box with the decelerating abutments.

20. In a straight knitting machine, the combination of a carrier rod, a drive rod, a friction box affording a driving connection between said rods, a slur cock bar, means for reciprocating said drive rod and slur cock bar in synchronization, relatively spaced narrowing nuts, travel stops for the carrier rod respectively mounted on said narrowing nuts, a bracket on each narrowing nut, a latch on each bracket for restraining the carrier rod during initial movement of the drive rod and slur cock bar, a cam slideable in each bracket for operating latch thereon, a lever pivoted to each bracket and operatively connected to the slide cam thereon, an abutment carried by each narrowing nut for engagement with the friction box, cams on the slur cock bar for operating said abutments for decelerating the friction box and carrier rod prior to the latter's engagement with the travel stops, and cams on the slur cock bar in predetermined relation to each other and to the abutment operating cams thereon for rocking said levers and thereby sliding the cams on the brackets for releasing the latches from the carrier rod in predetermined relation to the engagement of the friction box with the decelerating abutments.

PAUL SCHMIDT.
